UNITED STATES PATENT OFFICE.

ALEX H. JAHNSON, OF HICKSVILLE, NEW YORK, ASSIGNOR OF ONE-THIRD TO HERMAN MEYER, OF ROSLYN, NEW YORK.

SWIMMING-MACHINE.

1,193,394.

Specification of Letters Patent. Patented Aug. 1, 1916.

Application filed October 14, 1915. Serial No. 55,885.

To all whom it may concern:

Be it known that I, ALEX H. JAHNSON, a citizen of the United States, residing at Hicksville, Long Island, in the county of 5 Nassau and State of New York, have invented certain new and useful Improvements in Swimming-Machines; and I hereby declare that the following is a full, clear, and exact description thereof, reference being had to the accompanying drawings, 10 which form part of this specification.

This invention is a novel swimming machine or apparatus for use by swimmers.

Its object is to provide a light portable 15 machine by which a person can not only safely sustain himself in the water, but can readily propel himself through the water rapidly with small physical exertion.

The machine is light and can be easily 20 transported, can be packed in very small compass, and can be used as a life-saving apparatus in case of need as it possesses sufficient buoyancy to support a person in the water.

25 I will explain the invention as illustrated in the accompanying drawings, and summarize in the claims the essential novel features and combinations of parts of the invention for which protection is desired.

30 In said drawings: Figure 1 is a side elevation of the machine showing the manner of using same; Fig. 2 is a top plan view of such machine; Fig. 3 is a detail section on line 3—3, Fig. 2, looking in the direction of the 35 arrows with floats in operative position; Fig. 4 is an enlarged detail sectional view on the line 4—4, Fig. 1.

The machine as shown in the drawings 40 comprises a frame or supporting board 1 which is adapted to be placed in front of and against the body of the wearer when in the water; said frame 1 is preferably tapered from front to rear, and when in use projects in front of the swimmer, as indicated in Fig. 45 1; and the front end of this frame usually projects out of the water when the device is in use, and is preferably provided with a buoyant head 2, which may be of cork or other suitable make and which head insures 50 that the front end of the frame will remain above the surface of the water when the machine is in use. The frame is provided with a keel board or rib 3 near its end and on its underside, and said frame may have its rear 55 end widened as shown at 1^c so as to give it

a firm comfortable bearing against the body of the wearer when the device is in use.

Attached to the frame preferably near its rear end are a pair of floats 4 which are preferably adjustably connected to the frame by connections which will enable the floats to come above the surface near the shoulders of the wearer, as indicated in Fig. 1, so that the floats will support the wearer and frame in the water. These floats 4 may be of any suitable kind, and are preferably constructed so as to offer the least obstruction to the movement of the machine in the water. The floats may be provided with flexible straps 4^a of any suitable material, 60 preferably having two or more eyes or loops 4^b, any of which eyes can be engaged with a U-shaped holder 4^c, the ends 4^d of which holder are adapted to be sprung into engagement with eyes 5^a on the ends of a metal slide 70 5. The U-shaped holders have sufficient resiliency to make them to be engaged or disengaged at will from the eyes 5^a.

The slide connection enables the floats to be adjusted comfortably beneath the arms of the wearer, as shown in Fig. 1, and the slide 5 can be fastened in adjusted position by means of a screw and thumb nut 5^b as indicated in the drawings, or other suitable devices. By engaging the holders 4^c with different eyes 4^b of the straps 4 the floats can be connected to the body so as to support the wearer in more or less submerged position. 80

Attached to the upper side of the frame near the head thereof is a standard 6 which may be detachably and adjustably secured to the body. As shown it has a stud 6^c on its lower end adapted to engage any of a series of holes 1^c in the frame, and to be fastened in place by a thumb screw 6^b or other suitable 90 means. To the upper end of this standard is pivoted a double paddle shaft 7, which may be pivoted to a U-bracket 7^a in turn pivoted to the top of standard 6. The paddle shaft may have enlarged disks 7^b on its ends so as to have considerable surface in engagement with the water. 95

By reason of the pivoted engagement of the paddle shaft 7 with the bracket 7^a and the pivoted connection of the latter to the standard 6 the paddle can be operated like a double canoe-paddle, by the swimmer lying on the frame in the water; the swimmer grasping the paddle shaft with his hands, as indicated in Fig. 1, and operating the same 105 110

like a double canoe-paddle with perfect freedom.

With this machine the swimmer is supported in the water so that his head will be unsubmerged and he can freely use the paddle to propel himself with great speed through the water.

With this machine the resistance or friction offered to the passage of the swimmer through the water is reduced to the minimum.

The paddle disk or end is practically out of the water on its return movement, so that no resistance to the forward progress of the machine is caused by the paddles in making their return stroke; and when one paddle end is making its return stroke the other is acting effectively on the water to propel the swimmer; so no power is lost, and the swimmer is not compelled to make any extra exertion in order to return a paddle from the end of its active stroke to the beginning of its next active stroke. The angle at which the paddle shaft is pivoted to the standard is such that the paddle or disk on the end of the paddle shaft easily enters and leaves the water and practically the full broad side face of the paddle acts against the water when submerged. Of course when one end of the paddle shaft is in the water the other end is out so that, as stated, no resistance is offered by the paddles against the forward propulsion in the water.

The machine can be folded compactly so that it can be readily transported or it can be readily taken apart and packed in small space for transport or storage. The same frame can be comfortably used by persons of different size by adjusting the standard thereon in such position that the paddle shaft can be easily grasped and operated by the swimmer, and he can make full strokes with the paddle without feeling encumbered by the frame or floats. The floats are adjusted lengthwise of the frame so that the straps or connectors 4^a will come under the arms of the swimmer at the shoulders, and when properly adjusted to suit the height of the swimmer they can be fastened in position by manipulating the thumb nut 5^b. The straps 4^a are preferably provided with a plurality of eyes so that the same machine can be adjusted to suit people of different chest measurements. The U-shaped connectors 4^c can be easily sprung into or out of engagement with the eyes on the slide 5, and the holders 4^e engaged with the proper eyes of the straps 4^a to lengthen or shorten the distance between the floats according to the chest measurement of the wearer; and then the holder can be readily reengaged with the slides, and the machine is ready for use. The floats 4 may be made pneumatic or of any suitable material, though I prefer to make them of cork. I

also prefer to make the head on the front end of the frame of cork. The frame being tapered from front to rear offers less resistance to the water, and will remain more stable in contact with the body of the swimmer while he is using the machine. The widened or flared end 1^c of the frame gives such end a firm bearing against the body of the swimmer and assists in preventing oscillation of the machine while the swimmer is operating the paddles. As the standard and paddle are practically out of water when the machine is in use except so much of the paddle as may be momentarily engaged with the water at any time, this would be a dead weight upon the machine, but this is compensated for by the buoyant head 2 on the front end of the frame, and by the width of the front end of the frame which assists in balancing the machine and in supporting the dead weight thereon when the swimmer is in action.

What I claim is:

1. In a swimming machine, a frame, an oscillatory paddle supported on the front end of said frame, and floats connected with said frame in rear of the paddle and adapted to be adjusted to support the body of the swimmer, substantially as specified.
2. In a swimming machine the combination of a frame, floats connected with the frame so as to be adjustable to suit the swimmer, a standard mounted upon the front end of the frame, and a paddle pivotally connected with said standard adapted to be operated by the hands of the swimmer.
3. In a swimming machine the combination of a frame having a buoyant head and a keel, floats connected to the frame adapted to be adjusted to suit the swimmer, and a paddle pivotally connected to said frame so as to be operable by the hands of the swimmer.
4. In a swimming machine the combination of a frame having a keel, floats connected to the frame adapted to be adjusted to suit the swimmer, a standard adjustably attached to the front end of the frame, and a paddle pivotally connected to said standard so as to be operable by the hands of the swimmer.
5. A swimming machine comprising a frame having a keel, a pair of floats adjustably connected with said keel, and propelling devices attached to the front end of the frame and adapted to be actuated by the hands of the operator.
6. A swimming machine comprising a frame having a keel, a pair of floats adjustably connected with the rear end of said keel, a standard attached to the body and an oscillatory paddle pivotally mounted upon said standard and adapted to be operated by the hands of the swimmer.
7. A swimming machine comprising a

frame having a keel and a buoyant head, floats attached to the frame adapted to be adjusted to suit the swimmer, and a paddle attached to the forward end of the frame 5 adjacent the head thereof.

8. A swimming machine comprising a frame having a keel and a buoyant head, floats adjustably attached to the frame adjacent the rear end thereof, an oscillatory 10 paddle pivotally mounted upon the frame near the front end thereof adapted to be operated by the hands of the swimmer.

9. A swimming machine comprising a tapered frame having a buoyant head on its 15 larger end, floats adjustably attached to the frame adjacent the rear end thereof, and propelling devices attached to the forward end of the body adjacent the head thereof and adapted to be operated by the hands of 20 the swimmer.

10. A swimming machine comprising a

frame having a keel and a buoyant head, floats adjustably attached to the frame adjacent the rear end thereof, a standard adjustably attached to the frame near the 25 front end thereof, and an oscillatory paddle pivotally mounted upon said standard and adapted to be operated by the hands of the swimmer.

11. A swimming machine comprising a 30 tapered frame having a keel, a buoyant head, and a widened rear end, floats adjustably attached to the keel adjacent the rear end of the body, a standard adjustably attached to the frame near the front end 35 thereof, and an oscillatory paddle pivotally mounted upon said standard and adapted to be operated by the hands of the swimmer.

In testimony that I claim the foregoing 40 as my own, I affix my signature.

ALEX H. JAHNSEN.
